Inventor William H. Chandler

United States Patent Office.

WILLIAM H. CHANDLER, OF NORTH SCITUATE, RHODE ISLAND, ASSIGNOR
TO HIMSELF, JOHN WHEELER, AND EARL D. BARDET.

Letters Patent No. 75,624, dated March 17, 1868.

IMPROVEMENT IN MACHINE FOR STRAPPING AND GRINDING CARDS.

The Schedule referred to in these Letters Patent and making part of the same.

TO ALL WHOM IT MAY CONCERN:

Be it known that I, WILLIAM H. CHANDLER, of North Scituate, in the county of Providence, and State of Rhode Island, have invented an Improved Machine for Strapping and Grinding Cards; and do hereby declare that the following is a full and exact description, reference being had to the accompanying drawings, making a part of this specification.

The nature of my invention consists in the application of a simple mode of reversing motion to a machine for strapping and grinding cards.

To enable those skilled in the art to make and use my invention, I will proceed to describe its construction and operation.

Figure 1 represents a top view, showing the box within which the machine is enclosed.

Figure 2 represents a side view, with one side of the box removed for the purpose of showing the interior.

Figure 3 represents a top view of a portion of the machinery.

In the drawings, A represents a traveller, which moves back and forth in the slot B. Upon the traveller A are placed the rings or staples F F, to which the apparatus which operates upon the teeth of the cards is to be attached in any suitable manner. C is a hinged cover to the box or case, which encloses the machine. E E is the driving-shaft, and D the pulley. Upon the shaft E E is placed the worm G operating upon the gear-wheel H. This gear-wheel is attached to a shaft having a pulley, I, at one end. From this pulley a belt, J J, runs to the pulley I'. Upon the belt J J is secured the stud K, which moves with the belt around both pulleys. This stud enters a slot, L, in the lower part of the traveller A, thus causing such traveller to be moved back and forth in the groove B. M M are parallel guides for the lower part of the traveller.

What I claim as my invention, and desire to secure by Letters Patent, is—

The combination of a slot, L, in the traveller A, with a stud, K, belt, J J, and pulleys, I I', gear-wheel, H, and worm, G, substantially as and for the purpose specified.

WILLIAM H. CHANDLER.
